UNITED STATES PATENT OFFICE.

VICTOR ANGERER, OF RIDLEY PARK, AND ARTHUR B. DAVENPORT, JR., OF PHILADELPHIA, PENNSYLVANIA, ASSIGNORS TO WILLIAM WHARTON, JR., & COMPANY, INCORPORATED, OF PHILADELPHIA, PENNSYLVANIA, A CORPORATION OF PENNSYLVANIA.

TONGUE-SWITCH.

1,084,525.

Specification of Letters Patent.

Patented Jan. 13, 1914.

Application filed September 8, 1913. Serial No. 788,679.

To all whom it may concern:

Be it known that we, VICTOR ANGERER and ARTHUR B. DAVENPORT, Jr., citizens of the United States, and residents of Ridley Park, county of Delaware, State of Pennsylvania, and Philadelphia, county of Philadelphia, State of Pennsylvania, respectively, have invented certain Improvements in Tongue-Switches, of which the following is a specification.

One object of this invention is to improve the construction of a tongue switch of the type in which a portion of the body of a switch structure extends over a portion of the heel or pivot of the tongue.

Another object of the present invention is to provide a substantial base for the pivot portion of the tongue and to provide an adjustable base and means for yieldingly holding the pivot of the tongue to the base.

In the accompanying drawings:—Figure 1, is a plan view of sufficient of a tongue switch structure to illustrate our invention; Fig. 2, is a sectional view on the line *a—a*, Fig. 1; Fig. 3, is a transverse sectional view on the line *b—b*, Fig. 1; Fig. 4, is a sectional plan view on the line *c—c*, Fig. 2; Fig. 5, is a sectional view similar to Fig. 2, with the tongue removed; and Fig. 6, is a detached perspective view of the rear portion of the tongue of the switch.

Referring to the drawings, 1 is the body of the switch structure.

2 is the tongue resting on the depressed portion of the body, as illustrated in Fig. 2, and having a depressed pivot 3, in the present instance below the plane of the surface 4 of the body upon which the main portion of the tongue rests.

40 5 is an integral portion of the body extending over the depressed pivot of the tongue, as illustrated in Fig. 3.

The pivot 3 of the tongue fits into an annular bearing 15, the front portion of which is reduced in depth at 17, so that, by raising the tongue to the extent of the space 18 between the underside of the integral portion 5 of the switch body and the upper part of the pivot 3, it will be clear of the circular bearing and can be drawn forward in order to remove it from the body through the opening between the integral portion 5 and the vertical wall 19. The pivot further rests

on the circular base 6 adjustably secured to the body of the switch structure, so that, 55 when the main portion of the tongue rests on the surface 4, the base can be brought into simultaneous contact with the bottom of the pivot. In the present instance, this base is in the form of a screw plug having a 60 coarse thread 7 adapted to a similar thread 8 in the switch structure and after the plug is in place molten lead, or other metal, is poured into the space between the two threads, as indicated by dark lines, Fig. 2, 65 so as to hold the two parts firmly together after they have been properly adjusted in relation to each other. The base can be adjusted by a suitable tool, which can engage the lugs 20 on the interior of the base. 70

In order to hold the pivot 3 firmly on the base, we provide a spring bar 9, which extends laterally from one side of the opening to the other and rests in an inclined position against the inclined wall 10 of the pivot 3; 75 being engaged at one end by a lug 11 cast integral with the structure 1, and at the other end being secured to a rib 12 by a bolt 13 having a nut 14 which is adjustable so as to regulate the pressure of the spring 80 plate on the pivot 3. Thus, while the switch tongue can be turned, the tendency of the spring bar is to hold the pivot firmly on its seat or bottom bearing 6.

The spring plate 9 not only tends to force 85 the pivot down onto the base, but it also forces it against the rear portion of the circular bearing 15, making an exceedingly simple and substantial construction which will give a full bearing for the pivot of the 90 tongue. The spring plate 9 extends into a box 16 formed in one side of the switch structure and in this box is located the bolt 13 and its nut 14. The box is preferably provided with a suitable cover and, when 95 the cover is removed, access may be had to the box to adjust the spring plate or, by detaching the bolt, the spring plate can be bodily removed from the box, after which the tongue can be detached by raising it, so 100 that the pivot will clear the portion 17, and moving it forward so as to allow the pivot to pass from under the overhanging extension 5.

By the above construction, the pivot is 105 also held on the base by the annular bearing

so that, in the event of the spring plate becoming loose, the tongue cannot shift forward.

We claim:

5 1. The combination in a railway switch, of a body portion having a pivot opening and an annular bearing located below the pivot opening; said body also having an integral overhanging portion extending over 10 the bearing; and a tongue having a depressed pivot arranged to pass under the overhanging portion of the structure and to fit in the annular bearing.

2. The combination in a switch, of a body 15 having a recess and an annular bearing located in the recess, said body portion having a portion overhanging the annular bearing; a tongue having a depressed pivot arranged to pass under the overhanging portion of 20 the body; and a vertically adjustable base, within the bearing, on which the pivot rests.

3. The combination in a switch structure, of a body portion having a recess and having an integral portion extending over a 25 part of the recess; said body portion having an opening therein directly under the overhanging portion and said body portion having a screw thread; a base plug also having a screw thread meshing with the thread of

the body portion of the switch structure; 30 and a tongue having a depressed pivot arranged to pass under the overhanging portion of the structure and to rest upon the adjustable base.

4. The combination in a switch structure, 35 of a body portion having a recess to receive the switch tongue and having an overhanging portion at the pivot of the tongue; the body also having an annular bearing; an adjustable base within the bearing; a tongue 40 having a circular pivot depressed and extending at the rear thereof and under the overhanging portion, the front wall of the pivot being beveled; a transversely arranged diagonal spring bar resting on the 45 beveled portion of the pivot; and means for adjusting said bar so as to force the pivot against the base and against the rear of the circular bearing.

In testimony whereof, we have signed our 50 names to this specification, in the presence of two subscribing witnesses.

VICTOR ANGERER.
ARTHUR B. DAVENPORT, JR.
